UNITED STATES PATENT OFFICE.

LADISLAV F. KRISTUFEK, OF CHICAGO, ILLINOIS.

COMPRESSOR.

1,271,729.

Specification of Letters Patent.

Patented July 9, 1918.

Application filed December 19, 1913. Serial No. 807,600.

To all whom it may concern:

Be it known that I, LADISLAV F. KRISTUFEK, a citizen of the United States, and a resident of Chicago, in the county of Cook and State of Illinois, have invented certain new and useful Improvements in Compressors; and I do hereby declare that the following is a full, clear, and exact description thereof, reference being had to the accompanying drawings, and to the letters of reference marked thereon, which form a part of this specification.

This invention relates to rotary piston compressors and consists of the matters hereinafter described and more particularly pointed out in the appended claims.

To produce a compressor of the rotary piston type, which is efficient and capable of compressing fluid to the desired pressure to be of real commercial use, is the object of my invention. I attain this end in rotary piston compressors by providing certain leakage preventing packing means between the movable and stationary parts of the compressor. To assist in the further efficiency of compressors of the above type, it is advantageous in addition to the packing means before mentioned to construct the compressor so that the pressure of the fluid operated upon is raised in stages and to so raise the pressure, I provide a succession of cylindrical compression chambers of diminishing volumes, each chamber having a rotary piston therein, so arranged that the piston in each successive compression chamber will have about the same difference in pressure to work against as its predecessor thus decreasing the tendency toward leakage around the pistons.

In the drawings:

Figure 1 represents a longitudinal vertical section through an air compressor made in accordance with my invention.

Fig. 2 represents a transverse vertical section through the same, the said section being taken in a plane indicated by the line 2—2 of Fig. 1.

Figs. 3 and 4 are views similar to Fig. 2, the planes of the sections being indicated by lines 3—3 and 4—4 respectively of Fig. 1.

Fig. 5 is a plan sectional view through the air compressor, the plane of the section being taken on line 5—5 of Fig. 1.

Fig. 6 is a detail sectional view, the plane

of the section being taken in a plane indicated by the line 6—6 of Fig. 3.

Fig. 7 is a detail sectional view, the plane of said section being indicated by the line 7—7 of Fig. 4.

Referring now to that embodiment of my invention illustrated in the drawings, 10, 11 and 12 indicate a plurality of casing members arranged in axial alinement and all of the same general cross sectional shape, but 65 inclosing chambers of different volumes. 13 indicates a division wall or plate separating the casings 10 and 11. The said plate 13 is rigidly held in place between the casings 10 and 11 by means of screws 14 70 which pass through a flange 11^x formed on the casing 11 through the division wall 13 and into suitable threaded apertures in the peripheral wall of the casing member 10. 15 indicates a division wall or plate separating 75 the casings 11 and 12. The casing 12 is provided with an end plate or wall 16, said casings 11 and 12 and the plates or walls 15 and 16 having bosses adapted to receive screws or bolts which serve to secure 80 said casings and plates in proper relation.

In the lower part of each casing member 10, 11 and 12 are formed cylindrical compression chambers 10^a, 11^a and 12^a respectively. All of said chambers have their 85 central axes coincident and each is separated from the upper part of each casing by annular walls 10^b, 11^b and 12^b, said annular walls forming parts of the respective casings.

The respective casings above each compression chamber are divided by means of partition walls 10^c, 11^c and 12^c into inlet and outlet compartments 10^d, 10^e, 11^d, 11^e and 12^d and 12^e respectively. The casing 10 is provided with a plate or end wall 17 and 90 the inlet compartment 10^d of said casing is in communication with the atmosphere, or with any other source of fluid to be compressed through an aperture 18 formed in the wall of the casing 10. Said aperture is 100 provided with a screen 18^a to prevent the admittance of any foreign substance into the interior of the inlet compartment 10^d. The outlet compartment 12^e of the casing 12 has threaded thereinto a discharge pipe 105 19 for conveying the air or other fluid under pressure to a source of use.

Each end wall 16 and 17 is provided with an annular boss 16^a, 17^a respectively, in which are formed bearings for a main rota- 110

2
tively driven shaft 20, which shaft passes through apertures 13^a and 15^a respectively, provided therefor in the division plate 13 between the casings 10 and 11 and in the 5 plate 15 between the casings 11 and 12. The said shaft has its axis coincident with the central axis of the several compression chambers 10^a, 11^a and 12^a.

Within each of the cylindrical compression chambers 10^a, 11^a and 12^a are located eccentric members 21, 22 and 23, said eccentrics being keyed to the shaft 20 to rotate therewith. The eccentrics 22, 23 are arranged on the shaft 20 with their points of 15 greatest eccentricity separated by an approximate angle of 180 degrees from the eccentric 21. The said eccentrics are arranged to support and operate annular piston members 24, 25 and 26 respectively. 20 The construction arrangement and proportion of the parts is such that the rotation of the shaft 20 and of the eccentrics fixed thereto will cause the pistons 24, 25, 26 to roll upon the inner peripheral walls of their 25 respective chambers and thus act to compress the fluid in a familiar manner.

The detail construction of the various piston members and their associated parts in each casing is the same, the only difference 30 being in the size of the parts therein contained. It will suffice, therefore, to here give a description of one set of parts, namely, those contained in the casing 10 as 35 a sufficient disclosure of the construction of the parts contained within the other casings 11 and 12.

Referring now more in detail to the construction of the parts contained in the casing 10, the eccentric 21 comprises members 40 21^a and 21^c. The members 21^a have corresponding oppositely placed recesses 21^b and 21^c in which are located expansion coiled springs 21^c, 21^e, adapted to spread the members 21^a and 21^c apart so as to hold their 45 outer parts in close contact with the division wall 13 and the end wall 17 of the casing 10 and thus prevent leakage about the shaft where it extends through said walls. This construction also acts to compensate for the 50 expansion of the parts under the heat of friction.

The piston 24 mounted in and operated by the eccentric 21 is reduced in diameter in a part of its periphery as indicated at 24^a 55 in which part are provided longitudinally extending cylindrical bearing grooves 24^b which open through the periphery of the piston by means of slots 24^c of less width than the diameter of said cylindric grooves. 60 Mounted in said slots 24^c and capable of an oscillatory movement therein are contact shoes 27. Each of said shoes comprises a cylindric head part 27^a which has bearing relation within the associated groove 24^b in a 65 manner preventing displacement yet allow-

ing of an oscillatory movement of the shoe, and contact member 27^b which is adapted to engage the cylindrical wall of the compression chamber 10^a in the wiping movement of the piston and prevent the passage of fluid 70 between the piston and the adjacent peripheral surface of the casing wall. The head part 27^a and the contact member 27^b of the shoes are connected by a neck portion 27^c which is somewhat thinner than the width 75 of the slot 24^c.

It is apparent from the foregoing description that as the piston moves within the compression chamber 10^a, each shoe 27 will come into successive engagement with the cylindrical wall of the chamber 10 and will oscillate in the plane of rotation of the piston about the head 27^a as a pivot, under the action of the fluid undergoing compression which enters the spaces between the forward 85 ends of the shoes and the periphery of the piston members carrying them, thus providing a packing between the piston and chamber wall that will effectively hold the fluid under pressure and will adjust itself to accommodate for any wear on the contacting 90 surfaces.

The annular piston member 24 is provided with an integral, radially extending blade 28 which has sliding bearing in a slot 29 formed in an oscillating cylindrical bearing member 30. The said member 30 is of a length greater than the distance between the end wall 17 and the wall 13, said walls being provided with annular recesses 17^b and 13^b, 100 in which the ends of said member have bearing. The said bearing member 30 also has bearing in the wall 10^c that separates the compression chamber 10^a from the inlet and outlet compartments 10^d and 10^e. The bearing member 30 is provided in the slot thereof with a packing gland 31 which prevents leakage of air through said slot.

The blade 28 is provided in its lateral edges with grooves 28^a, 28^b extending the full 110 length of the blade. In each groove 28^a and 28^b are packing bars of metal or other suitable material 32, 32. 33, 33 indicate laterally extending, vertically spaced recesses which open outwardly into the grooves 28^a, 28^b. In said recesses 33, 33 are located spring-controlled pins 34, 34 which act to hold the outer edges of the packing bars 32, 32 in engagement with the walls 17 and 13 and at the same time prevent vertical displacement of said bars in their respective grooves. This construction prevents leakage of air between the lateral edges of the blade and the walls 17 and 13 against which they contact. This construction also compensates for wear of the parts and for the 120 expansion thereof due to the heat of friction.

40 indicates an aperture in the wall 10^c for the passage of fluid from the inlet com- 130

partment 10^d to the compression chamber 10^a. 41 indicates a similar aperture formed in said wall 10^b for the discharge of fluid under pressure from the compression chamber 10^a into the outlet compartment 10^e. In said outlet compartment is located a spring controlled check valve 42, which prevents the return of fluid from the outlet compartment, back into the associated compression chamber.

10 In the wall 13 is provided an aperture 13^c which aperture communicates at one end with the interior of the outlet compartment 10^e. The aperture 13^c at its opposite end 15 registers with a groove 11^y formed in the flange of casing 11 and opening into the inlet compartment 11^d of the casing 11. The wall 15 separating the casings 11 and 12 is provided with an aperture 15^e, one end of 20 said aperture opening into the outlet compartment 11^e, the other end opening into the inlet compartment 12^d of the casing 12, thus establishing communication between the outlet compartment 11^e and the inlet compartment 25 12^d.

It is apparent from the foregoing description that the fluid drawn into the compression chamber 10^a is initially compressed therein and is discharged therefrom at a predetermined pressure above the initial pressure by means of the piston 24 into the outlet compartment 10^e. The fluid thence passes through the aperture 13^c in the wall 13 and through the groove 11^y formed in the flange of the casing 11, into the inlet chamber 11^d of the casing 11 at the same pressure as that at which it leaves the outlet compartment 10^e. The fluid then leaves the compression chamber 11^a to be compressed to a higher pressure and is discharged into the outlet compartment 11^e of the casing 11 from which it passes through the aperture 15^e in the wall 15 into the inlet compartment 12^d of the casing 12 at the same pressure at which it was discharged from the compression chamber 11^a. In the compression chamber 12^a, it is again compressed whence it will be discharged into the outlet compartment 12^e to pass through 50 the pipe 19 on its way to its source of use.

In this manner the fluid is compressed in the first compression chamber to a predetermined point above its initial pressure, is then compressed in the second chamber to a still higher pressure, and so on successively in the several chambers until the required high pressure is reached.

It is possible to compress air to a high pressure with a small machine of this type, 60 hence a great deal of expense in both the original cost of the machine and the maintenance of the same is saved.

It will be noted that in my improved construction, a flexible packing is provided between the surface of the piston and the

inner peripheral surface of the compression chamber, and in the particular embodiment of the invention shown herein, this flexible packing is applied to the piston. It is manifest, however, that the invention is not limited to its application to the piston as it might equally well be applied to the peripheral wall of the compression chamber. While in respect to this feature of the invention as well as in respect to other features, I have referred to, described and illustrated various details of mechanical construction and arrangement, it is to be understood that the invention is in no way limited thereby except as pointed out in the appended claims.

While I have illustrated and described my invention in connection with a pumping device for compressing gases, for which purpose my invention was more particularly devised, it will be readily understood that the feature of my invention relating to the packing between the piston and the compression-chamber is of utility in a liquid pump, it being my intention by the appended claims to protect my invention accordingly.

I claim as my invention:—

1. A compressor comprising a casing providing a cylindrical compression-chamber 95 having an inlet and a discharge, a piston member in said compression-chamber adapted to have orbital movement, means for orbitally moving said piston member, and means providing packing intermediate said 100 piston member and the peripheral wall of said compression-chamber comprising a plurality of oscillatory members.

2. A compressor comprising a casing providing a cylindrical compression-chamber 105 having an inlet and a discharge, a piston member in said compression chamber adapted to have orbital movement, means for orbitally moving said piston member, and means providing packing intermediate said 110 piston member and the peripheral wall of said compression-chamber comprising a plurality of oscillatory members carried by said piston member.

3. A compressor comprising a casing providing a cylindrical compression chamber having an inlet and a discharge, a piston member in said compression chamber adapted to have orbital movement, means for orbitally moving said piston member, and 120 means providing packing intermediate said piston member and the peripheral wall of said compression chamber comprising a plurality of members adapted for oscillating movement in the plane of the movement of 125 said piston.

4. A compressor comprising a casing providing a cylindrical compression chamber having an inlet and a discharge, a piston member in said compression chamber adapt- 130

4
ed to have orbital movement, means for orbitally moving said piston member, and means providing packing on the surface of said piston member consisting of members carried by said piston member and capable of oscillation in the plane of movement of said piston.

5. A compressor comprising a casing providing a cylindrical compression chamber
10 having an inlet and a discharge, a piston member in said compression chamber adapted to have orbital movement, means for orbitally moving said piston member, and packing between said piston member and the peripheral wall of said compression chamber comprising members pivoted on said piston member with spaces between the latter and the forward ends of said members open to the interior of said chamber,
15 whereby the fluid, while undergoing compression, operates against said members and holds them in contact with the peripheral wall of said chamber.
20 6. A compressor comprising a casing providing a cylindrical compression-chamber,
25

having an inlet and a discharge, a piston member in said compression-chamber adapted to have orbital movement, means for orbitally moving said piston member, and packing between said piston member and the peripheral wall of said compression-chamber comprising members mounted on said piston member to have movement relative thereto, with spaces between the piston member and the forward ends of said last-named members open to the interior of said chamber, whereby the fluid, while undergoing compression, operates against said last-named members and holds them in contact with the peripheral wall of said chamber.

In testimony, that I claim the foregoing as my invention I affix my signature in the presence of two witnesses, this 16th day of December, A. D. 1913.

LADISLAV F. KRISTUFEK.
